US0D1113441S

(12) **United States Design Patent** (10) **Patent No.:** **US D1,113,441 S**
(45) **Date of Patent:** **** Feb. 17, 2026**

(54) **BOTTLE CAP**

(71) Applicant: **Origin Materials Operating, Inc.**,
West Sacramento, CA (US)

(72) Inventors: **Jay Clarke Hanan**, West Sacramento,
CA (US); **Rachel Hess**, West
Sacramento, CA (US)

(73) Assignee: **Origin Materials Operating, Inc.**,
West Sacramento, CA (US)

(**) Term: **15 Years**

(21) Appl. No.: **29/930,550**

(22) Filed: **Feb. 29, 2024**

(51) **LOC (15) Cl.** **09-07**

(52) **U.S. Cl.**

USPC **D9/453**

(58) **Field of Classification Search**

USPC D9/434, 435, 447, 448, 442, 446, 449,
D9/450, 451, 452, 453, 454, 499
